UNITED STATES PATENT OFFICE.

KENNETH RUSHTON, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

RADIAL DRIVING-WHEEL FOR LOCOMOTIVES.

1,355,699.

Specification of Letters Patent. Patented Oct. 12, 1920.

Application filed September 10, 1919. Serial No. 322,818.

To all whom it may concern:

Be it known that I, KENNETH RUSHTON, a citizen of the United States, residing in Philadelphia, Pennsylvania, have invented 5 certain Improvements in Radial Driving-Wheels for Locomotives, of which the following is a specification.

My invention relates to certain improvements in locomotives, particularly those of 10 the narrow gage type, in which there is a series of driving wheels at each side.

One object of the invention is to design the locomotive so that a pivoted driving axle may be located at one or both ends 15 thereof.

A further object of the invention is to provide a bearing mounted on a fixed axle from which the end wheels adapt themselves on a radius.

20 A still further object of the invention is to construct the locomotive so that the axles are carried by an outside frame and the pivoted wheel structure is mounted between the frames and on the axle.

25 Another object of the invention is to provide the axle with a rectangular section to which are adapted blocks mounted in the wheel structure and to provide springs for allowing a certain amount of lateral movement.

30 In the accompanying drawings:

Figure 1 is a plan view, showing the frame and the four axles of a narrow gage type of locomotive;

35 Fig. 2 is a longitudinal sectional view on the line 2—2, Fig. 1;

Fig. 3 is a transverse sectional view, drawn to an enlarged scale, of one of the end axles of the wheel structure;

40 Fig. 4 is a transverse sectional view on the line 4—4, Fig. 3;

Fig. 5 is a perspective view of one of the curved coupling blocks, and

45 Fig. 6 is a view illustrating a locomotive in which the pivoted driving wheels are at one end and the ordinary pivoted truck wheels are at the opposite end.

Referring to the drawings, 1, 1 are the side frames of the locomotive of the ordinary type having pedestals to receive the boxes 2 in which the axles 3, 3 and 4, 4 are mounted. In the present instance, the locomotive is illustrated as provided with four axles and four driving wheels at each

side. All of the axles are adapted to boxes, 55 and the wheels 5 are secured to the axles 3. The wheel structures 6 are mounted on the axles 4 and while they must turn with the axle they are free to swing to accommodate curves. 60

On each axle is a crank disk 7 having a pin 8. These pins are connected by the usual rods 9 and one of the pins of the central axles is elongated to receive the main connecting rod 10. 11 is a central bearing frame mounted on the two axles 3, 3, which are shouldered, as at 12, to retain the bearing in the central position. The bearing is provided with boxes 13 adapted to each axle 3, and the two bearings are connected together by a tube 14, in the present instance, although this construction may be varied. The central frame 11 carries at its end a pivot pin 15 to which the radius frame 16 is pivoted. This frame consists of a V-shaped member 17 and two cylindrical bearings 18, which are securely bolted to the member 17. These bearings encircle the portions 19 of the wheel structure 6 and allow the said structure to swing so that the 75 wheels 20, to which these portions are rigidly attached, will accommodate themselves to the curves of the rails.

In order to drive the wheel structure from the shaft, which is adapted to fixed boxes, I 80 make the center 21 of the shaft square, as shown in Figs. 3 and 4, and form a box 22 on the wheel structure having four recesses to which are adapted the curved coupling blocks 23. The interior of the box 22 85 is curved and each block is curved to correspond with it. The blocks, as shown in Fig. 5, have vertical sides, which fit the side walls of the recess in the coupling so that when motion is imparted to the shaft 90 21 the strain is taken by walls of considerable area.

In order to assemble the parts, I make the wheel structure in two sections, each section having a flange 24, secured together by 100 bolts 25. While I have shown the wheel center 26 forming an integral part of the portion 19 of the wheel structures, they may be separate and bolted thereto, if found desirable. In the present instance, there is a 105 cap plate 27 secured to the portions 19, and between this cap plate and the follower ring 30 at each end of the wheel structure is a

heavy coiled spring 31. One wall of this follower ring is curved, as shown, the curve being taken from the center of the shaft, and bearing against this ring is a second curved ring 32, which fits snugly on the portion 33 of the shaft 4. There is one of these rings on each side of the center, as shown clearly in Fig. 3. The opening in the ring 30 is much larger than the shaft so that the shaft can have considerable movement without interfering with the ring 30 and the same is the case with the cap plate 27, the opening in which is much larger than the shaft. The ring 32 is less in diameter than the opening in the wheel structure and located between this ring and a shoulder 4 on the structure is a ring 35. While one wall of this ring is also curved to correspond with the curve of the ring 32, the other wall fits snugly against the shoulder.

When the locomotive is passing around a curve, there is a tendency for the shaft to move longitudinally. In order to allow for this movement, I locate the springs 31 on each side of the coupling so that when this longitudinal movement takes place one of the springs yields to allow this movement, while the wheels are retarded by the rails, but as soon as the locomotive passes to the straight track the springs return the structure to the central position. There is a small amount of lost motion to allow the wheels to accommodate themselves to the track.

35 I preferably insert a bearing strip between the two rings 30 and 32, as shown. I provide an opening 36, closed by a screw plug 37, to permit lubricant to be placed within the structure.

40 In Fig. 6, I have illustrated a frame of a locomotive, in which there are three driving axles 3^a, 3^a and 4^a. The axles 3^a have the wheels rigidly secured thereto, while the wheel structure is pivotally mounted on the axle 4^a. The wheels 38 (shown in diagram) are carried by the ordinary truck, or pilot, and are not driven. In this figure, the curved tracks 39 are also shown, the driving wheels on the axle 4^a accommodating themselves to the track.

45 It will be seen by the above construction that I am enabled to build a locomotive with three or more driving axles, and to mount a wheel structure on a driving axle at one end, or on a driving axle at both ends of the structure with means by which the wheel structure can swing independently of its axle in passing around curves and the pivots for the wheel structures are carried on a central frame supported by shafts having fixed wheels of the ordinary construction.

50 While my invention is especially adapted for use in connection with narrow gage loco-

motives, it will be understood that it can be used with other types of locomotives as well.

55 It is especially adapted for use in connection with locomotives in which the frames are outside of the driving wheels.

I claim:

1. The combination in a locomotive, of a series of axles; boxes for the axles; frames in which the boxes are mounted; a central axle having driving wheels fixed thereon; an end driving axle extending from one side of the locomotive to the other and having a wheel structure swiveled thereon, the axle having a series of flat surfaces at its center, the wheel structure having a series of recesses therein opposite said flat surfaces; blocks mounted in the recesses having a flattened surface bearing upon the flat surfaces of the axle, and having their sides abutting the side walls of the recesses, and means for driving the several axles, motion being imparted to the wheel structure from its axle through the boxes.

2. The combination in a locomotive, of a frame; driving axles thereon; wheels mounted on the two intermediate axles; a wheel structure pivotally mounted on one end axle; a bearing supported by each of the intermediate axles to which the wheel structure is directly pivoted; and a coupling connecting the end axle with its wheel structure so that the wheel structure must turn on its axle, but is free to swivel thereon.

3. The combination in a locomotive, of side frames; a series of driving axles each axle extending from one side frame to the other and adapted to bearings in the frames; means for driving the axles, wheels located on the intermediate axles between the frames, a wheel structure on each end axle also located between the frames, the said wheel structure having a series of recesses therein, each end axle having flat surfaces at the center, blocks mounted in the recesses in the wheel structure having flattened surfaces bearing upon the flat surfaces of their respective axles and having their remaining surfaces abutting the walls of the recesses within which they are mounted, and wheels rigidly secured to the wheel structures.

4. The combination in a locomotive, of a frame; driving axles mounted in bearings in the frame; means for driving the axles in unison; fixed wheels on the intermediate axles a wheel structure swiveled on an end axle, and arranged to be turned by said axle; a cap plate at each end of the wheel structure; a follower ring at each side of the center; a spring between each cap plate and each follower ring; one wall of each follower ring being concaved and a ring free to slide on the axle at each side of the center.

and having one face concaved to fit the concaved surface of the follower ring and having the other face concaved; a ring on each side of the center bearing against a shoulder 5 on the wheel structure and having a convex curved surface to fit the concaved surface of the ring on the axle.

5. The combination in a locomotive, of a frame; driving axles mounted in the frame; 10 means for driving the axles in unison; wheels fixed to the intermediate axles, a wheel structure on an end axle, the said end axle having flat surfaces at the center the wheel structure being recessed opposite the

flat surfaces and blocks located in the recesses and bearing upon the flat surfaces and free to slide longitudinally thereon, a spring at each side of the center, the outer end of each spring bearing against the wheel structure, a follower ring at each side of the center against which the other end of each spring finds its bearing; a ring at each side of the center and sliding on a reduced portion of the axle and taking the thrust of the springs and arranged to allow the wheel structure to have a lateral movement independent of the axle.

KENNETH RUSHTON.
